MARINE FLOAT
A B De Jarnett, 1016 Maryland Ave.,
West Sacramento, Calif.
Filed Dec. 27, 1962, Ser. No. 248,837
4 Claims. (Cl. 114—5)

This invention relates to marine floats and more particularly to floating docks, covered and open berths, boat houses, swimming floats, work platforms, and the like.

In the past numerous types of floats have been used. These normally use a wooden deck structure from which all structural strength is developed plus a means of floatating this structure such as logs, barrels, polystyrene planks, concrete pontoons and Fiberglas cells. Other types have used individually formed units which included both the floatation and the deck structure coupled together by wood stringers along the side. The conventional material for this type of float is concrete. A recent innovation in this method is the use of Fiberglas.

The instant invention uses individually formed units including both floatation and deck and contemplates as a primary object, an improved structure of floatation unit and the means of providing the structural strength required.

An additional important object of this invention is to provide a labor saving method of and apparatus for installation of floating docks or the like. Conventional docks require skilled labor to construct the deck structure over water, which is extremely costly. If constructed on land and launched, the heavy structures are subject to damage and are extremely difficult to handle. This invention provides a method of construction whereby two men can handle an individual unit, placing it in position and attaching it to the floating structure. The use of conventional concrete reinforcing materials and special concrete accessories provides a product requiring little in the way of special equipment and assures a ready supply of materials for its construction. Here again costs have been pared over conventional docks.

A further important feature of this invention is the buyer may install it using any desired deck material. A conventional wood deck, a piece of plywood, Masonite, or specially formed Fiberglas decking providing beauty as well as utility.

A further object is the easy removal of individual units of the structure. Units may be removed by removing bolts through the side stringers for replacement in case of damage or for cleaning marine life, etc. The entire structure may be removed and relocated at little expense and without damage.

Another object is the maintenance of a more constant freeboard of the floating structure. The individual units when attached adjacent to each other maintain a constant level of deck. Spot loading distributes the load to several floats and makes little difference in freeboard. However, an extreme load such as may be applied by building some additional structure or supporting a ramp will bring additional floatation into use in an increasing ratio due to the sloping side surfaces of the pontoon.

The units composing a feature of the instant invention may be formed in convenient sizes without costly remodeling of the mold.

Still other objects reside in the combinations of elements, arrangements of parts, and features of construction, all as will be more fully pointed out hereinafter and disclosed in the accompanying drawings wherein:

FIGURE 1 is a top plan view of a plurality of floats joined by stringers, partially broken away, comprising an element of the instant inventive concept.

FIGURE 2 is a vertical longitudinal sectional view

2

taken substantially along the line 2—2 of FIGURE 1 is viewed in the direction indicated by the arrows;

FIGURE 3 is a horizontal sectional view taken substantially along the line 3—3 of FIGURE 2 as viewed in the direction indicated by the arrows but with the stringers not shown;

FIGURE 4 is a vertical longitudinal sectional view taken substantially along the center plane 4—4 of FIGURE 3 as viewed in the direction indicated by the arrows;

FIGURE 5 is an enlarged vertical transverse sectional view taken substantially along the line 5—5 of FIGURE 2 as viewed in the direction indicated by the arrows but with the stringers not shown, the left side being considered the portside and the right side being considered the starboard;

FIGURE 6 is an enlarged vertical transverse sectional view taken substantially along the line 6—6 of FIGURE 2 as viewed in the direction indicated by the arrows but with the stringers not shown, the port and starboard portions considered the same as for FIG. 5; and

FIGURE 7 is an enlarged fragmentary detail, in horizontal sectional view showing a constructional detail.

Similar reference characters refer to similar parts throughout the several views of the drawings.

Having reference now to the drawings in detail, there is generally indicated at 10 a float unit constructed in accordance with the instant inventive concept. Each individual float is comprised of a framework of steel rods, which in the illustrative embodiment shown, includes spaced parallel longitudinally extending top rods 11 connected by transversely extending end rods 12, and a plurality of transverse stringers 13. Lower longitudinally extending rods 14 are vertically aligned with rods 11, and vertical connecting stringers 15 at spaced intervals connect rods 11 and 14. Vertical rods 15 are bent inwardly as at 16 to form lower horizontal portions 17 and thence bent upwardly as at 18 to form angularly disposed portions 19 which contact and are secured to adjacent transverse members 12 or 13 in accordance with their position. All rod connections are securely welded to afford a tight and secure unitary wire cage or frame.

Pairs of crossed or diagonally disposed reinforcing members 20 extend in vertical planes at each end frame angularly from one end of each upper rod 11 to each opposite end of the opposite lower rod 14 to afford a substantially rigid cagelike frame structure, which provides a foundation for the float member per se, to be described hereinafter.

Bolt sockets, to be more fully described hereinafter, are attached to the cage or frame at predetermined intervals intervals and in desired localities, and the cage is then placed in a mold. Obviously, the cage or frame and its associated mold may be of any desired convenient size, although in actual practice a section of approximately 8 feet in length by 4 feet in width has been found desirable for convenience in handling.

The mold is then filled with plastic foam, by injection, or other desired method, until the steel frame is covered to a minimum depth of 3 inches overall. During the molding process the bolt sockets are held in aligned relation with the edges of a mold in any desired conventional manner, and, after completion of the plastic foam injection, the completed floats may be removed from the mold.

In finishing each float a suitable deck 25 is applied to the upper surface thereof and secured thereto by bolts 27 engaged in sockets 26. The bolts and sockets are standard loop coil concrete accessories readily available at construction hardware suppliers and are comprised of

helically wound heavy duty wire of a thickness corresponding to the grooves in the bolt, and a U-shaped reinforcing wire securing loop 29 is secured to the exterior of the helix, with its bight extended around the adjacent rod 11, or such other rod as may be immediately adjacent thereto, with the rod being passed through the loop formed by the U-shaped member 29 prior to the welding of the cage or frame in its desired position. Suitable washers 30 may be positioned beneath the bolt heads as desired. The deck may be of any suitable material, such, for example, as tempered Masonite, laminated Fiberglas, plywood, or conventional wood may be employed. The vertical bolts and sockets passing through the deck to a rod in the frame are in tension, and as the deck is fastened tightly to the top of the plastic foam, the outer top layer of foam particularly in the areas around the vertical bolts is in compression.

Similar bolts 27 may be employed in identical sockets 26 extending laterally through the sides of the plastic foam to secure wooden side stringers 31 thereto. The horizontal bolts and sockets passing through the side stringers to a rod in the frame are in tension, and as the stringers are fastened tightly to the sides of the plastic foam, the outer side layers of foam particularly in the areas around the horizontal bolts are in compression. In the preferred arrangement two centrally positioned sockets are provided as best seen in FIGURE 1 and two end sockets so that the stringers may extend half the length of adjacent aligned floats 10 to secure the aligned floats in related assembly.

The cross-sectional shape of the float is best shown in FIGURES 5 and 6 wherein there is a relatively thin central body portion 35 provided on its underside with a channel 36 on either side of which depend side portions 37, to afford stability and lightness. The ends of channel 36 are closed by plastic foam skirts 38, and the sides of the channel are inclined inwardly and upwardly as at 39, thus affording a stable, relatively light weight float which is centrally provided normally with an air space which increases the normal buoyancy of the device. The longitudinal edges of the float have greater vertical dimensions than the center or longitudinal axis of the float and thus as seen in FIGS. 5 and 6 the float may be said as having two pontoons or two keels, a design which is well known for its superior stability against pitching as compared to a flat bottom float.

Obviously, the floats may be assembled in any desired pattern and connected longitudinally, transversely in multiples, or used individually as desired.

From the foregoing it will now be seen that there is herein provided an improved marine float, which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

I claim:

1. A marine float comprised of a plurality of metal rods and a plurality of attached metal bolt socket elements, all joined to form a unitary box-like frame,

a cover of molded plastic foam completely encasing said frame, so as to provide a uniformly solid buoyant mass with the exception of said frame and bolt sockets,

the outside of the float being shaped as a rectangular parallelopiped

but deviating therefrom by the presence of a large central bottom cavity extending part way towards the float top,

said cavity being in transverse elevation of decreasing horizontal dimension upwardly with respect to a vertical center plane extending fore and aft of the float,

and of a maximum transverse width about one-half the total beam of the float,

said cavity providing greater transverse stability against pitching than a float which is of exact rectangular parallelopiped shape,

said plurality of attached metal bolt socket elements all facing outwardly, some socket elements being horizontal and some socket elements being vertical, all socket elements attached to said frame at spaced points thereof and extending completely through the exterior skin portions of said molded plastic foam cover,

whereby during molding the frame may be supported and positioned with respect to its mold by threading horizontal bolts through the mold sides and into the horizontal socket elements,

and whereby during flotation use of the float, horizontal stringers may be compressed against the longitudinal sides of the cover of plastic foam by threading horizontal bolts through the stringers and into the horizontal socket elements,

and whereby during floatation use of the float, a deck may be compressed against the top of the cover of plastic foam by threading vertical bolts through such deck and into the vertical socket elements.

2. A flat top marine float comprised of a plurality of metal rods joined together to form a three dimensional rigid unitary cage or frame,

a cover of molded plastic foam completely and outwardly uniformly encasing said cage or frame, and providing a uniform fill at all float cross-sections between and around said rods,

transverse vertical cross-sections of the float having a rectangular and straight line perimeter with the exception of the bottom line which extends in the center half upwardly and centrally converging, thus defining a cavity, said cavity extending about half way towards the top of the float and for the full longitudinal extent of the float,

vertically upwards and outwardly facing bolt sockets secured at spaced distances along an upper outer rod of said cage or frame and extending to the exterior horizontal top face of said cover, and a flat deck compressibly secured to said top face of said cover by bolts extending tightly into said vertical sockets,

horizontal and outwardly facing bolt sockets secured at spaced distances along said upper outer rod of said cage or frame and each extending to a closer vertical face of said cover,

and side stringers compressibly secured to the outer vertical side faces of said cover by bolts extending tightly into said latter horizontal sockets.

3. The structure of claim 2 wherein two side stringers are secured to each outer side face of a float by utilizing at least two bolts and sockets per single stringer,

each stringer being of a length substantially equal to the longitudinal dimension of the float, and having one end mounted closely and equally adjacent the mid-longitudinal length of the float,

whereby approximately one-half the length of each stringer extends beyond the ends of the float for connection to an adjacent float.

4. A flat top marine float comprised of a plurality of metal rods joined together to form a three dimensional, rigid, unitary boxlike cage, protected outwardly thereof by a homogeneous cover of plastic foam, and provided inwardly between said rods with a homogeneous fill of the same material,

the top of said cage including an oblong perimeter of rods and two diagonals from opposite corners, the outer ends of said cage each including as top rods the said perimeter rods of the ends of the oblong, a vertical continuation of each end of said last rods to form connecting stringers, lower inwardly directed

horizontal portions and final upwardly bent portions which connect to medial portions of said top rods, the outer ends of said cage also including diagonal rods, one of said diagonal rods extending from the top of one stringer at one side to the bottom of the other stringer, and a second one of said diagonal rods extending from the top of the other stringer to the bottom of the one stringer,

the outer sides of said cage including as top rods the perimeter rods of the sides of said oblong, the connecting stringers of the ends, horizontal lower rods similar to the said latter top rods and a plurality of short diagonal rods connecting the latter top rods and lower rods, the lower end of each short diagonal rod being closer to the longitudinal middle of the unit, and the upper end of each short diagonal rod therefor being closer to the end of the unit,

whereby the cage is stiffened against deformation in a horizontal plane and each principal vertical plane, and

a plurality of metal bolt sockets attached to said cage and directed outwardly to the outer adjacent surface of the foam cover, and

whereby planar surface elements may be compressibly held against outer surfaces of the foam cover, by 25

threading bolts inwardly through the surface elements and tightly into the bolt sockets.
